UNITED STATES PATENT OFFICE.

THOMAS BARTHOLOMEW, OF COLUMBUS, OHIO.

TOY.

1,162,674.

Specification of Letters Patent.

Patented Nov. 30, 1915.

Application filed September 22, 1915. Serial No. 52,003.

To all whom it may concern:

Be it known that I, THOMAS BARTHOLOMEW, a citizen of the United States, residing at Columbus, in the county of Franklin and State of Ohio, have invented certain new and useful Improvements in Toys, of which the following is a specification.

This invention relates to toys and aims particularly to simulate the action of a hoop when the same is given a forward twirling thrust. This action is perhaps well known, since to make the hoop rotate about its center of gravity, will cause it to travel lineally along the ground when in frictional engagement with the ground and when given a forward thrust, the two forces conflict until finally one predominates. This twirling action may then, by a little skill, be governed so as to predominate to cause a return movement of the hoop when it strikes a floor or table top.

The main object of my invention, therefore, resides in the provision of a split or open spring hoop structure, one end of which is so shaped that a grip is formed for causing a flexing of the ring as a whole to permit its escape and at the same time to give it a twirling action. This grip is preferably designed for coaction with the thumb of the operator, although not necessarily so. However, a further object is to form the grip so it will coact with the thumb of the operator by bending one end out laterally so that it projects out of the plane of the hoop as a whole.

A further object of my invention consists of a base unit to be used in combination with this hoop structure, this base unit being provided with a suitably formed groove out of which the hoop is permitted to escape after it has been properly flexed.

Still a further object is to form the hoop with an anchor portion designed for coaction with the base unit to aid the operator in properly positioning the hoop prior to the flexing operation.

The preferred embodiment of my invention is shown in the accompanying sheet of drawings, in which similar characters of reference designate corresponding parts, and in which:

Figure 1 represents the manner of using my invention in connection with a base member to be applied to the finger of the operator, Figs. 2, 3 and 4 are side elevation, top plan and end elevational views showing an-

other manner of using my improved hoop structure, Fig. 5 is a view showing the split hoop by itself, and, Figs. 6 and 7 are side elevation and top plan views of the type of base unit used when operating the hoop in the manner illustrated in Fig. 1.

The hoop is represented by the reference numeral 1 and is constructed of wire containing the necessary degree of resiliency. This hoop is split, as is shown at 2, to present an open formation, and the end of the foremost portion 3 is then turned or bent laterally as is shown at 4, this particular location of the right angularly turned portion 4 being when the split portion 2 is uppermost. This arrangement permits the convenient grasping by the second finger and thumb as is indicated in Fig. 1. In order that the hoop may have a firm base from which it may slide, I have provided the second finger with a base member in the form of a ring 5 provided with a groove as is shown at 6 for properly guiding the ring in its outward movement. To aid the operator in properly positioning the hoop with relation to the base member, I have formed it with a crimp or anchor portion 3^a located as shown in the drawings.

As is illustrated in Fig. 1, the gradual depression of the portion carrying the right angular bend 4 causes this bent portion to move beyond the natural center of gravity and when this point is reached, the frictional grip between the base member 5 and the base portion of the ring will be overcome to cause a forward thrust of the ring, due to its inherent resiliency. The third finger may also be used to start the ring in its movement, if desired, by a slight forward pressure toward the base member 5 when the hand has assumed a position as is shown in Fig. 1. At the same time, the downward pressure caused by the thumb and the engagement between the ring and base grip 5 also causes a rotative action of the ring about its center of gravity. This causes a twirling of the ring which tends to decrease the impetus of the forward thrust after the ring strikes the ground or other surface upon which it operates and thus the impetus is gradually overcome while the continued rotation of the ring as a whole, will then frictionally grip the surface upon which it operates to cause its return to a point approximately near the starting point by a rolling action.

In the type of structure shown in Figs. 2, 3 and 4, the base member is designated by the reference numeral 7 and comprises merely a slab having an elongated groove 8 adjacent one edge into which the hoop structure is placed after the manner illustrated and then operated in a manner similar to that above outlined. I preferably resort to this type of construction when the toy is used for advertising purposes, since the space 9 of the slab 7 may conveniently be used for advertising purposes to display the name of the donor.

From the foregoing description, it will be apparent that I have provided a toy which will afford considerable amusement and which, by a little practice, may be skilfully operated by persons of all ages.

What I claim, is:

- 20 1. A toy comprising an open spring hoop, one end of which hoop is shaped to present a grip portion for use in flexing the hoop.
2. A toy comprising an open spring hoop, one end of which is bent out laterally to form a thumb grip.
3. A toy comprising an open spring hoop, the foremost end of which is bent laterally to the right when the open portion is at the top of the hoop.
- 30 4. A toy comprising an open spring hoop, one end of which is bent out laterally to form a thumb grip, and a base member formed with a groove out of which the hoop is to slip when it is properly flexed.
- 35 5. A toy comprising an open spring hoop,

one end of which is bent out laterally to form a thumb grip and that portion of which opposite said bend is formed with a crimp to serve as an anchor portion.

6. A toy comprising an open spring hoop, 40 one end of which is bent out laterally to form a thumb grip and that portion of which opposite said bend is formed with a crimp to serve as an anchor portion, and a base member formed with a groove out of 45 which the hoop is to slip when it is properly flexed.

7. A toy comprising an open spring hoop, the foremost end of which is bent laterally to the right when the open portion is at the 50 top of the hoop, and a ring to fit the finger of the operator against which the hoop is designed to rest.

8. A toy comprising an open spring hoop, the foremost end of which is bent laterally 55 to the right when the open portion is at the top of the hoop, that portion of said hoop opposite said bend being formed with a crimp to serve as an anchor portion, and a ring to fit the finger of the operator, said 60 ring being formed with a groove into which said crimped portion is designed to seat itself.

In testimony whereof I affix my signature in presence of two witnesses.

THOMAS BARTHOLOMEW.
